UNITED STATES PATENT OFFICE.

LOUIS J. VAN GUELLEN, OF CINCINNATI, OHIO.

PERFORATING MACHINE.

Application filed November 18, 1919. Serial No. 338,956.

To all whom it may concern:

Be it known that I, LOUIS J. VAN GUELLEN, a citizen of the United States, residing at the city of Cincinnati, in the county of Hamilton and State of Ohio, have invented certain new and useful Improvements in Perforating Machines, of which the following is a specification.

The object of my invention is to produce a compact and highly efficient machine for perforating shoe tips, vamps, foxings, sweat bands in hats, parts of gloves, and any other part or parts of shoes, boots and the like, or any other parts of any article of manufacture, or the article itself, and the machine can be used to place these perforations in leather, cloth, rubber, canvas, paper, or any other flexible material.

This machine is preferably used to form a continuous line of perforations, evenly spaced, but may be made to form perforations with wider spaces between them, and may be adjusted to allow wider or narrower spaces between such perforations, as may be required.

One of the salient features of my invention enables me to perforate flat work, on a flat plate or support and also enables me to perforate this flat work, after it has been sewed up and closed, in the shape of a ring, annulus, oval or any other irregular or peculiar form and this I accomplish on a cylinder or cylindrical arm.

In punching or perforating under the system now in vogue, the paper which is used under the material while the perforating is taking place, (and which paper is used as a cushion or the like), runs, or is fed in the same direction as the material, and in alignment with the perforations; whereas in my machine the paper is fed and moves at right angles to the material being punched or perforated.

In the accompanying drawing, forming part of this specification:

Fig. 1, is a longitudinal section of the main supporting arm of the machine, the operative parts being in elevation the rounded arm being also in elevation,

Fig. 2, is a front elevation of my machine,

Fig. 3, is a sectional view on the line 3—3 of Fig. 1,

Fig. 4, is a sectional view on the line 4—4 of Fig. 1,

Fig. 5, is a sectional view on the line 5—5 of Fig. 1,

Fig. 6, is a sectional view on the line 3—3 of Fig. 1, the section showing only through the rounded arm,

Fig. 7, is a sectional view of the lower 60 part of the punch bar,

Fig. 8, is a view in elevation of the paper or cushion feed mechanism,

Fig. 9, is an elevation partly in section of the punch feed mechanism, on line 9—9 65 of Fig. 4,

Fig. 10, is a plan view of the feed plate or work support,

Fig. 11, is a plan of one form of shoe vamp open and before closed and stayed, 70

Fig. 12, is a plan view of the vamp shown in Fig. 11, after it has been closed and stayed,

Fig. 13, is a view in elevation, looking at the vamp from the rear, after it has been 75 closed and stayed,

Fig. 14, is a plan view of a shoe vamp and foxing not sewed together,

Fig. 15, is a plan view of the vamp and foxing after the same have been sewed together, 80

Fig. 16, is a plan view of a circular vamp,

Fig. 17, is a plan view of a shoe tip,

Fig. 18, is an isometric view of the work supporting arm and part of the machine, 85 which is broken away,

Fig. 19, is a similar view, a closed vamp being however shown in position on the supporting arm, ready for perforating, with part of the punch shown, and 90

Fig. 20, is a view of the arm in elevation (or a side view), and part of the machine broken away, the arm also partly broken away to show construction.

I provide a hollow arm, formed of a base 95 part 1, an upright part 2 and a forwardly extending part 3; the arm being connected to a table or bench through medium of base part 1.

In the part 2 of the arm, I journal a drive 100 or cam shaft 4, carrying on the outside a drive pulley 5 and a hand wheel 6, made integral. In the part 3 of the arm, I journal a rock shaft 7. Between the shaft 4 and shaft 7, I place, in part 2 of the arm, a 105 stud 8, (see particularly Fig. 1). In part 2 of the arm, on the drive shaft 4, I rigidly attach two cams 9 and 10. The cam 9 (see particularly Fig. 5) is so shaped that two of its parts or surfaces will always be in 110 contact with the fork arms 11. The cam 10 (see particularly Fig. 4), is the same in

shape and size as cam 9 and two of its surfaces or parts are always in contact with the ways 12 of housing 13. At the inner end of drive or cam shaft 4, I rigidly attach a spiral gear 14, meshing with a spiral gear 15, on short shaft 16 (see particularly Figs. 1 and 6). On the stud 8, I loosely attach a lever 17, and at the upper part, said lever carries a segment gear 18 which meshes with 10 a segment gear 19, which is adjustably attached to the rock shaft 7. The lower part of the lever 17 carries a forked or bifurcated end, the arms of which end are marked 11.

The cam or drive shaft 4 passes through 15 an elongated slot in the housing 13, an up and down motion being given to the housing 13, as the cam 10 is passing and revolving and coming in contact with the ways 12, the slot 20 preventing a lateral motion there- 20 to. At the top of housing 13, I provide a stem 21 which is loosely connected by stud 22 to one end of an arm 23, the other end of the arm is fulcrumed at 24 by a stud attached to the frame part 2 of the arm; the 25 said arm at this end carrying a segment 25 provided with a segmental slot 26; the arm 23 and the segment 25 being made integral. A slide block 27 works loosely in the slot 26 and is connected by a stud 28 to 30 an arm 29, which arm is connected loosely at its inner end to a lever 30 by a stud 31. The lever 30 is adjustably attached to a sleeve 32 which works loosely on shaft 7. On the forward end of sleeve 32, is a down- 35 wardly and forwardly extending arm 32¹, made integral therewith. At the outer end of the arm 29, I provide an adjusting pin 33, which at its inner end carries a finger 34 which is placed on pin 32, out of center 40 thereon. The segment 25 carries a multiplicity of staggered holes 35, into which the finger 34 enters and registers by manual operation. A slot 36 is provided in part 2 of the arm to accommodate part of the 45 mechanism set forth.

The above mechanism just described has to do with the movement of the punch laterally or sidewise, and will be more fully described hereafter.

50 I will now describe the forward and backward movement of the punch bar housing. The punch bar housing is made up of a frame formed of an upper bearing 37 and a lower bearing 38, connected by two side bars 39—39, each bearing supported by a horizontal slide shaft 40—40. A U-shaped piece 41, extending upwardly from the lower bearing 38 carries a slide block 42, said slide block being loosely connected by a stud 43, 55 rigidly connected in the end of the arm 32¹ and, as the sleeve 32 and arm 32¹ oscillate, the housing just described moves forward and backward.

I will now refer to the mechanism for 60 operating the punch bar up and down. At

the forward end of the rock shaft 7, I connect a crank 44; at the lower end of this crank I connect a stud 45 which carries a slide block 46, said block working in a slot 47 in the punch bar holder 48; said punch bar holder being adjustably connected to the punch bar 49, by means of the said punch bar being screw threaded into the punch bar holder 48. Near the center or the middle of the horizontal bearings 37 and 38, and extending forwardly therefrom, I provide two vertical bearings 50—50, said bearings keep the punch bar in alignment and support the same so that it can properly move up and down, acting like sleeves for 80 the punch bar.

The punch bar 49, at its lower extremity carries a cutting tube holder 51, inserted into the bottom of said punch bar and is provided with a flange or collar 52, threaded on 85 its periphery to receive the threaded collar 53 which rests on a shoulder 54 on the punch bar, and thus the tube holder is held in the punch bar 49. At the bottom of the punch holder, I place the cutting tube or tubes 55; the cutting tube is hollow and the punch holder has a hole 56, aligned with the hole in the cutting tube so that the punchings are forced up into the recess 57 in the punch bar and finally work out of the side of the 90 punch bar, at 58, (see particularly Fig. 7).

I provide an arm 59, formed like a bracket, which is cast integral with the part 2 of the upwardly extending arm. This arm or bracket forms the punching anvil at 100 point 60, and supports the feeding plate and the paper feed mechanism.

The feed plate is marked 61 and is formed as shown in Fig. 10, having a locking yoke 62 by means of which it is attached to the arm 59 by a screw 63; it can thus be removed at will without changing or readjusting any of the mechanism. On this feed plate I support flat work, as shown in Figs. 11, 14, 16 and 17, and this plate is removed 110 when I do closed work, shown in Figs. 12, 13 and 15.

I will now describe the two paper feeding rolls 64 and 65, both of which have a roughened or knurled face; the roller 64 is inside the arm 59 and is loosely supported on a bearing 66 on a stud 70, said bearing extending from one of the side walls 67 of the arm 59; the roller 65 is below the arm and is supported in a bearing 68 on a shaft 71 and 115 rigidly attached thereto. The bearing 68 is attached to a bracket 69, on the lower part of arm 59, (see particularly Figs. 1, 2 and 3). The extending shaft 71 of the roller 65 carries at its outer end a ratchet wheel 72 and also an arm 73, at the upper end of which I place a ratchet pawl 74 which operates and revolves the ratchet wheel 72; at the lower end of arm 73 I loosely attach a link or connecting bar 75 which at its oppo- 120 125 130

site end is loosely attached to a lever or crank 76; said crank being rigidly attached to shaft 16.

On the shaft 71, I adjustably attach a guide 77, having a flange 78 projecting over said ratchet wheel 72, on which flange the pawl 74 rides; and after riding over the face of said flange engages one of the teeth of said ratchet wheel; being adjustably attached by moving said guide and its flange backward or forward, the pawl can be made to engage one tooth at a different point on the face of the ratchet, so that it will move or turn the ratchet wheel more or less, as desired, so that the paper 79, used as a cushion, will be fed forward to a greater or less extent by the paper feed rolls 64 and 65. This paper may be guided and held in alignment by any suitable means (not shown).

At the forward end of the arm 59, I place two rolls 80 and 81, over which the paper passes. The paper 79 is held on a spool or reel (not shown), and from this point 25 travels up through slots 82 and 83, in the arm 59, and thence over the top of the arm 59, under the punch bar 49, and then over the rolls 80 and 81 back through the paper feed wheels 64 and 65.

30 I will now describe a guide for the material to be worked upon. Underneath part 3 of the arm, I provide a lug 84 and in this lug I connect a small shaft 85, which carries a downwardly and forwardly extending arm 86, adjustably attached to shaft 85, and at its end, said arm carries a peculiarly shaped foot 87, adjustably attached; said foot 87 carries a small spring 88 at its forward end to keep the material from turning or buckling up at its edge. This spring also acts as a stripper as the punch tube 55 recedes from the leather or material worked upon.

35 In Fig. 11, I show a long vamp 89, open and not sewed, having perforations 90 around its inner edge. The operator must use his or her own judgment as to where the stitching will be located, from the edge 91, and, if the perforations come too close to said edge 91, when the vamp is closed, the staying stitching 92 (see Figs. 12 and 13) may, by chance, pass through some of the perforations and thus make a defective shoe. In Fig. 12, the vamp 89, has perforations 90 and is the vamp shown in Fig. 11, except that it has been closed and stayed, the staying stitches being marked 92. When the vamp is in this condition, the operator can make no mistake, as she can readily observe the staying stitches and thus perforate accordingly; and this closed vamp can be perforated on my machine, as will be herein-after described.

40 In Fig. 14, I show a vamp 93 having foxing 94, having perforations 90, and in

Fig. 15, I show the vamp closed and stayed by stitching 95 and 96. If the operator must perforate the vamp and foxing separately, as shown in Fig. 14, then said operator must guess where to begin perforating at the edges 97 and 98, and the stitching 95 or 96 may pass into some of the perforations in both places, or in either place, thus producing a defective shoe.

45 By using my machine the operator can see where to begin and stop, the same as in perforating the vamp shown in Fig. 12.

The vamp 99, shown in Fig. 16, is known as a circular vamp and cannot be sewed together before perforating, because it must be done flat or spread out.

50 In Fig. 17, I show a shoe tip 100, which must be perforated flat before being sewed to the shoe vamp.

The feed plate 61 has a slot 101, (see Fig. 10). At the top of the arm 59, which top part of said arm is flat, and at the outer edges of said arm, I form recesses 102, (see Figs. 2 and 3), which are as deep as the thickness of the plate at this point, so that when the plate 61 is slipped into these recesses, it will lie flush with the top of the arm and thus form a continuous flat surface, after the screw 63 has been set and tightened on the bottom of arm 59. When flat work is to be done on this machine, for the convenience of the operator, and to secure results, this plate 61 is used; but, when closed work and the like is to be done, some forms of which are shown in Figs. 12, 13, and 15, the feed plate 61 is removed and the work is done on the arm 59, inasmuch as this arm is cylindrical and rounded, (see particularly Figs. 18, 19, and 20); and such work can be placed or hung on the arm as shown in Fig. 19, where the vamp marked 89, is shown in position. In operating the machine motion is transmitted to shaft 4 through pulley 5, which shaft revolves and thus turns cam 9, this in turn moves lever 17, which oscillates the segment gears 18 and 19, and the gear 19 being adjustably attached to rock shaft 7, and thus this shaft is rocked or oscillated. At forward end of this shaft 7 is connected the crank 44, which being operated by the said shaft 7, in turn, with its connections to the punch bar holder 48; which is adjustably connected to punch bar 49, reciprocates the punch bar holder 48, consequently the punch bar 49 and the punch tube 55 are also reciprocated.

55 The revolving shaft 4 also revolves cam 10, which in turn reciprocates the housing 21, the lever 23 and the segmental slide way 25, the lever 29 being attached thereto is reciprocated horizontally, and, being attached to lever 30, which in turn is adjustably attached to sleeve 32, on rock shaft 7, oscillates the said sleeve 32. At the forward end of the lever 32 is a lever 32¹ attached

60 to sleeve 32, which sleeve 32 is adjustably attached to sleeve 32¹, which sleeve 32¹ is adjustably attached to sleeve 32², which sleeve 32² is adjustably attached to sleeve 32³, which sleeve 32³ is adjustably attached to sleeve 32⁴, which sleeve 32⁴ is adjustably attached to sleeve 32⁵, which sleeve 32⁵ is adjustably attached to sleeve 32⁶, which sleeve 32⁶ is adjustably attached to sleeve 32⁷, which sleeve 32⁷ is adjustably attached to sleeve 32⁸, which sleeve 32⁸ is adjustably attached to sleeve 32⁹, which sleeve 32⁹ is adjustably attached to sleeve 32¹⁰, which sleeve 32¹⁰ is adjustably attached to sleeve 32¹¹, which sleeve 32¹¹ is adjustably attached to sleeve 32¹², which sleeve 32¹² is adjustably attached to sleeve 32¹³, which sleeve 32¹³ is adjustably attached to sleeve 32¹⁴, which sleeve 32¹⁴ is adjustably attached to sleeve 32¹⁵, which sleeve 32¹⁵ is adjustably attached to sleeve 32¹⁶, which sleeve 32¹⁶ is adjustably attached to sleeve 32¹⁷, which sleeve 32¹⁷ is adjustably attached to sleeve 32¹⁸, which sleeve 32¹⁸ is adjustably attached to sleeve 32¹⁹, which sleeve 32¹⁹ is adjustably attached to sleeve 32²⁰, which sleeve 32²⁰ is adjustably attached to sleeve 32²¹, which sleeve 32²¹ is adjustably attached to sleeve 32²², which sleeve 32²² is adjustably attached to sleeve 32²³, which sleeve 32²³ is adjustably attached to sleeve 32²⁴, which sleeve 32²⁴ is adjustably attached to sleeve 32²⁵, which sleeve 32²⁵ is adjustably attached to sleeve 32²⁶, which sleeve 32²⁶ is adjustably attached to sleeve 32²⁷, which sleeve 32²⁷ is adjustably attached to sleeve 32²⁸, which sleeve 32²⁸ is adjustably attached to sleeve 32²⁹, which sleeve 32²⁹ is adjustably attached to sleeve 32³⁰, which sleeve 32³⁰ is adjustably attached to sleeve 32³¹, which sleeve 32³¹ is adjustably attached to sleeve 32³², which sleeve 32³² is adjustably attached to sleeve 32³³, which sleeve 32³³ is adjustably attached to sleeve 32³⁴, which sleeve 32³⁴ is adjustably attached to sleeve 32³⁵, which sleeve 32³⁵ is adjustably attached to sleeve 32³⁶, which sleeve 32³⁶ is adjustably attached to sleeve 32³⁷, which sleeve 32³⁷ is adjustably attached to sleeve 32³⁸, which sleeve 32³⁸ is adjustably attached to sleeve 32³⁹, which sleeve 32³⁹ is adjustably attached to sleeve 32⁴⁰, which sleeve 32⁴⁰ is adjustably attached to sleeve 32⁴¹, which sleeve 32⁴¹ is adjustably attached to sleeve 32⁴², which sleeve 32⁴² is adjustably attached to sleeve 32⁴³, which sleeve 32⁴³ is adjustably attached to sleeve 32⁴⁴, which sleeve 32⁴⁴ is adjustably attached to sleeve 32⁴⁵, which sleeve 32⁴⁵ is adjustably attached to sleeve 32⁴⁶, which sleeve 32⁴⁶ is adjustably attached to sleeve 32⁴⁷, which sleeve 32⁴⁷ is adjustably attached to sleeve 32⁴⁸, which sleeve 32⁴⁸ is adjustably attached to sleeve 32⁴⁹, which sleeve 32⁴⁹ is adjustably attached to sleeve 32⁵⁰, which sleeve 32⁵⁰ is adjustably attached to sleeve 32⁵¹, which sleeve 32⁵¹ is adjustably attached to sleeve 32⁵², which sleeve 32⁵² is adjustably attached to sleeve 32⁵³, which sleeve 32⁵³ is adjustably attached to sleeve 32⁵⁴, which sleeve 32⁵⁴ is adjustably attached to sleeve 32⁵⁵, which sleeve 32⁵⁵ is adjustably attached to sleeve 32⁵⁶, which sleeve 32⁵⁶ is adjustably attached to sleeve 32⁵⁷, which sleeve 32⁵⁷ is adjustably attached to sleeve 32⁵⁸, which sleeve 32⁵⁸ is adjustably attached to sleeve 32⁵⁹, which sleeve 32⁵⁹ is adjustably attached to sleeve 32⁶⁰, which sleeve 32⁶⁰ is adjustably attached to sleeve 32⁶¹, which sleeve 32⁶¹ is adjustably attached to sleeve 32⁶², which sleeve 32⁶² is adjustably attached to sleeve 32⁶³, which sleeve 32⁶³ is adjustably attached to sleeve 32⁶⁴, which sleeve 32⁶⁴ is adjustably attached to sleeve 32⁶⁵, which sleeve 32⁶⁵ is adjustably attached to sleeve 32⁶⁶, which sleeve 32⁶⁶ is adjustably attached to sleeve 32⁶⁷, which sleeve 32⁶⁷ is adjustably attached to sleeve 32⁶⁸, which sleeve 32⁶⁸ is adjustably attached to sleeve 32⁶⁹, which sleeve 32⁶⁹ is adjustably attached to sleeve 32⁷⁰, which sleeve 32⁷⁰ is adjustably attached to sleeve 32⁷¹, which sleeve 32⁷¹ is adjustably attached to sleeve 32⁷², which sleeve 32⁷² is adjustably attached to sleeve 32⁷³, which sleeve 32⁷³ is adjustably attached to sleeve 32⁷⁴, which sleeve 32⁷⁴ is adjustably attached to sleeve 32⁷⁵, which sleeve 32⁷⁵ is adjustably attached to sleeve 32⁷⁶, which sleeve 32⁷⁶ is adjustably attached to sleeve 32⁷⁷, which sleeve 32⁷⁷ is adjustably attached to sleeve 32⁷⁸, which sleeve 32⁷⁸ is adjustably attached to sleeve 32⁷⁹, which sleeve 32⁷⁹ is adjustably attached to sleeve 32⁸⁰, which sleeve 32⁸⁰ is adjustably attached to sleeve 32⁸¹, which sleeve 32⁸¹ is adjustably attached to sleeve 32⁸², which sleeve 32⁸² is adjustably attached to sleeve 32⁸³, which sleeve 32⁸³ is adjustably attached to sleeve 32⁸⁴, which sleeve 32⁸⁴ is adjustably attached to sleeve 32⁸⁵, which sleeve 32⁸⁵ is adjustably attached to sleeve 32⁸⁶, which sleeve 32⁸⁶ is adjustably attached to sleeve 32⁸⁷, which sleeve 32⁸⁷ is adjustably attached to sleeve 32⁸⁸, which sleeve 32⁸⁸ is adjustably attached to sleeve 32⁸⁹, which sleeve 32⁸⁹ is adjustably attached to sleeve 32⁹⁰, which sleeve 32⁹⁰ is adjustably attached to sleeve 32⁹¹, which sleeve 32⁹¹ is adjustably attached to sleeve 32⁹², which sleeve 32⁹² is adjustably attached to sleeve 32⁹³, which sleeve 32⁹³ is adjustably attached to sleeve 32⁹⁴, which sleeve 32⁹⁴ is adjustably attached to sleeve 32⁹⁵, which sleeve 32⁹⁵ is adjustably attached to sleeve 32⁹⁶, which sleeve 32⁹⁶ is adjustably attached to sleeve 32⁹⁷, which sleeve 32⁹⁷ is adjustably attached to sleeve 32⁹⁸, which sleeve 32⁹⁸ is adjustably attached to sleeve 32⁹⁹, which sleeve 32⁹⁹ is adjustably attached to sleeve 32¹⁰⁰, which sleeve 32¹⁰⁰ is adjustably attached to sleeve 32¹⁰¹, which sleeve 32¹⁰¹ is adjustably attached to sleeve 32¹⁰², which sleeve 32¹⁰² is adjustably attached to sleeve 32¹⁰³, which sleeve 32¹⁰³ is adjustably attached to sleeve 32¹⁰⁴, which sleeve 32¹⁰⁴ is adjustably attached to sleeve 32¹⁰⁵, which sleeve 32¹⁰⁵ is adjustably attached to sleeve 32¹⁰⁶, which sleeve 32¹⁰⁶ is adjustably attached to sleeve 32¹⁰⁷, which sleeve 32¹⁰⁷ is adjustably attached to sleeve 32¹⁰⁸, which sleeve 32¹⁰⁸ is adjustably attached to sleeve 32¹⁰⁹, which sleeve 32¹⁰⁹ is adjustably attached to sleeve 32¹¹⁰, which sleeve 32¹¹⁰ is adjustably attached to sleeve 32¹¹¹, which sleeve 32¹¹¹ is adjustably attached to sleeve 32¹¹², which sleeve 32¹¹² is adjustably attached to sleeve 32¹¹³, which sleeve 32¹¹³ is adjustably attached to sleeve 32¹¹⁴, which sleeve 32¹¹⁴ is adjustably attached to sleeve 32¹¹⁵, which sleeve 32¹¹⁵ is adjustably attached to sleeve 32¹¹⁶, which sleeve 32¹¹⁶ is adjustably attached to sleeve 32¹¹⁷, which sleeve 32¹¹⁷ is adjustably attached to sleeve 32¹¹⁸, which sleeve 32¹¹⁸ is adjustably attached to sleeve 32¹¹⁹, which sleeve 32¹¹⁹ is adjustably attached to sleeve 32¹²⁰, which sleeve 32¹²⁰ is adjustably attached to sleeve 32¹²¹, which sleeve 32¹²¹ is adjustably attached to sleeve 32¹²², which sleeve 32¹²² is adjustably attached to sleeve 32¹²³, which sleeve 32¹²³ is adjustably attached to sleeve 32¹²⁴, which sleeve 32¹²⁴ is adjustably attached to sleeve 32¹²⁵, which sleeve 32¹²⁵ is adjustably attached to sleeve 32¹²⁶, which sleeve 32¹²⁶ is adjustably attached to sleeve 32¹²⁷, which sleeve 32¹²⁷ is adjustably attached to sleeve 32¹²⁸, which sleeve 32¹²⁸ is adjustably attached to sleeve 32¹²⁹, which sleeve 32¹²⁹ is adjustably attached to sleeve 32¹³⁰, which sleeve 32¹³⁰ is adjustably attached to sleeve 32¹³¹, which sleeve 32¹³¹ is adjustably attached to sleeve 32¹³², which sleeve 32¹³² is adjustably attached to sleeve 32¹³³, which sleeve 32¹³³ is adjustably attached to sleeve 32¹³⁴, which sleeve 32¹³⁴ is adjustably attached to sleeve 32¹³⁵, which sleeve 32¹³⁵ is adjustably attached to sleeve 32¹³⁶, which sleeve 32¹³⁶ is adjustably attached to sleeve 32¹³⁷, which sleeve 32¹³⁷ is adjustably attached to sleeve 32¹³⁸, which sleeve 32¹³⁸ is adjustably attached to sleeve 32¹³⁹, which sleeve 32¹³⁹ is adjustably attached to sleeve 32¹⁴⁰, which sleeve 32¹⁴⁰ is adjustably attached to sleeve 32¹⁴¹, which sleeve 32¹⁴¹ is adjustably attached to sleeve 32¹⁴², which sleeve 32¹⁴² is adjustably attached to sleeve 32¹⁴³, which sleeve 32¹⁴³ is adjustably attached to sleeve 32¹⁴⁴, which sleeve 32¹⁴⁴ is adjustably attached to sleeve 32¹⁴⁵, which sleeve 32¹⁴⁵ is adjustably attached to sleeve 32¹⁴⁶, which sleeve 32¹⁴⁶ is adjustably attached to sleeve 32¹⁴⁷, which sleeve 32¹⁴⁷ is adjustably attached to sleeve 32¹⁴⁸, which sleeve 32¹⁴⁸ is adjustably attached to sleeve 32¹⁴⁹, which sleeve 32¹⁴⁹ is adjustably attached to sleeve 32¹⁵⁰, which sleeve 32¹⁵⁰ is adjustably attached to sleeve 32¹⁵¹, which sleeve 32¹⁵¹ is adjustably attached to sleeve 32¹⁵², which sleeve 32¹⁵² is adjustably attached to sleeve 32¹⁵³, which sleeve 32¹⁵³ is adjustably attached to sleeve 32¹⁵⁴, which sleeve 32¹⁵⁴ is adjustably attached to sleeve 32¹⁵⁵, which sleeve 32¹⁵⁵ is adjustably attached to sleeve 32¹⁵⁶, which sleeve 32¹⁵⁶ is adjustably attached to sleeve 32¹⁵⁷, which sleeve 32¹⁵⁷ is adjustably attached to sleeve 32¹⁵⁸, which sleeve 32²⁹⁸ is adjustably attached to sleeve 32²⁹⁹, which sleeve 32²⁹⁹ is adjustably attached to sleeve 32³⁰⁰, which sleeve 32³⁰⁰ is adjustably attached to sleeve 32³⁰¹, which sleeve 32

to a slide on the punch bar housing, said punch bar housing being loosely attached on shafts 40-40, which in turn move the punch bar housing laterally.

5 The stock to be worked upon is placed under the punch and against the guide part 87 and under the spring 88; the machine is then started, (the paper cushion 79 being always fed at right angles or different direction, and under the material or stock, at all times); the punch descends through the material and partly into the paper cushion 79; the punch then recedes and pulls out of the paper cushion until the lower cutting 15 face of the cutting tube 55 is flush with the top face of said paper cushion; then the punch moves laterally, carrying the material along with it, to the point indicated by the spacing mechanism heretofore set forth; at 20 which point the stock holding means (not shown), any form of which may be employed, holds the stock against the top part of arm 59, where it is used as an anvil (part 60); the punch then receding out of the 25 material to its highest position; then the punch moves forward and is ready for another descent to punch the next perforation; and continuing to reproduce this action until the stock is perforated as desired or 30 needed.

This machine is power operated and the power can be stopped at any time desired. If it is desired to operate the machine to any position, the operator can do it by hand 35 through the medium of the hand wheel 6.

Some attempts have been made to perforate a stayed vamp, or similar article of manufacture on a perforating machine, but such attempts have been mechanically and 40 commercially unsatisfactory; however, on my machine, on account of its peculiar construction, such work can be mechanically and commercially, successfully accomplished.

Although I have described one form of 45 my machine specifically in this application,

I wish to be understood as claiming any modified form thereof.

What I claim as new and my invention and desire to secure by Letters Patent is:

1. In a machine of the class described, a 50 perforating means and mechanism for operating the same, means for supporting the material to be perforated and a cushion thereunder, both traveling under the perforating means and means for forcing the material to travel in one direction and the cushion at approximately right angles to the material.

2. In a machine of the class described, a 55 perforating means and mechanism for operating the same, means for supporting the material to be perforated and a cushion thereunder, both traveling under the perforating means and means for forcing the material to travel in one direction and the cushion traveling at right angles to the material.

3. In a machine of the class described, a 60 perforating means, mechanism for operating the same, a feed plate and an arm, both for supporting material to be perforated, the feed plate supporting flat material and the arm supporting closed material to be perforated, and means for supporting and guiding the material through the perforating 65 operation.

4. In a machine of the class described, a 70 reciprocating perforating means, mechanism for operating the same, the material to be perforated and a cushion for supporting 75 said material traveling under the perforating means, and being operated upon simultaneously, the material and the cushion traveling at right angles to one another, both before and after the perforating operation. 80

In testimony whereof, I affix my signature at Cincinnati, Ohio, this 12th day of November, 1919.

LOUIS J. VAN GUELLEN.
